UNITED STATES PATENT OFFICE.

WILLIAM VEENSCHOTEN, OF HORNELLSVILLE, NEW YORK.

ELEVATOR.

SPECIFICATION forming part of Letters Patent No. 494,658, dated April 4, 1893.

Application filed July 14, 1892. Serial No. 440,051. (No model.)

To all whom it may concern:

Be it known that I, WILLIAM VEENSCHOTEN, a citizen of the United States, residing at Hornellsburg, in the county of Steuben and State of New York, have invented a new and useful 5 Elevator, of which the following is a specification.

My invention relates to an elevator designed especially for basements, cellars, &c., of private houses and buildings where the use of such a device is insufficient to justify the employment of steam, water, or electric power.

The object of my invention is to provide a simple, cheap, and safe elevator for the purpose named, which can be operated by hand by the person upon the elevator.

The construction of my improvement is fully described hereinafter, and the novel features are particularly pointed out in the appended claims.

In the drawings: Figure 1 is a perspective view of an elevator embodying my invention. Fig. 2 is a bottom plan view of the car. Fig. 3 is a vertical sectional view of the car and well. Fig. 4 is a detail view of the door-locking device.

My improved elevator is preferably arranged in the landing of the cellar steps, as indicated in the drawings, the car A comprising a platform B, which corresponds with said landing when the car is in its elevated position, the vertical support C and the top or cover D, which fills the opening in the landing when the car is in its lower position. The car is attached to the end of a cable E, which extends over a pulley F, and carries a weight G, having a case containing the independent weights g. By means of the independent weights, the weights g may be regulated or adjusted to suit the load. Upon the under side of the car is arranged a system of bolts forming a locking device to sustain the elevator in the desired position.

H H are the transverse sliding bolts, fitting in guides h, and K K are bell-crank levers, having the extremities of their outer arms connected to the inner ends of said bolts.

The foot-lever L is pivoted to the floor of the car with its horizontal arm arranged above the plane thereof, and its lower or vertical arm connected at its extremity to the extremities of the inner arms of the bell-crank levers

by the rods M. The locking-bolts are provided with collars N, and coiled springs O are arranged upon the bolts to bear against said collars to normally hold the bolts in their locking positions. When the free end of the foot-lever is depressed, it draws upon the connecting-rods M and swings the outer arms of the bell-crank levers inwardly, thereby retracting 60 the locking-bolts and disengaging them from the catches P, which are shown upon the walls of the well.

Q represents a hand-rod, which passes through aligned openings in the floor and roof 65 of the car within reach of the operator, said rod being stationary to enable the car, when properly balanced by its weight above described, to be moved either upward or downward.

Attached to each door which opens into the well of the elevator, is a locking device comprising a horizontal spring-actuated bolt R, connected at its rear end to one arm of a bell-crank lever S, the other arm of said lever being connected by means of a rod T to the pivoted detent U, which extends outwardly into the path of the elevator in its descent. The locking-bolt is normally held in its locking position in engagement with a suitable socket 75 in the door-jamb, and when the elevator descends to the plane of the bottom of the door it engages said detent and depressing the latter, withdraws the bolt and releases the door.

The cable is attached to the car by means 85 of an eye-bolt V, the shank of which extends vertically downward through the roof of the car and is engaged at the lower surface of the latter by the thumb-nut W. By means of this device the cable may be shortened or lengthened, as required.

The operation of my improved elevator will be readily understood from the above description.

Having thus described my invention, what 95 I claim, and desire to secure by Letters Patent, is—

1. In combination with an elevator car, the sliding, spring-actuated locking-bolts, the pivoted foot-lever arranged close to the floor of the car, and means of connection between the foot-lever and the locking-bolts, substantially as specified.

2. In an elevator, the combination with a

counter-balanced car, of a locking mechanism comprising the sliding spring-actuated bolts, projecting at their outer ends beyond the sides of the car, the bell-crank levers having their outer arms connected to the inner extremities of said bolts, the angular foot-lever having its horizontal arm arranged above the plane of the floor of the car and the rods connecting the lower arm of the foot-lever to the inner arms of the bell-crank levers, substantially as specified.

3. The combination with an elevator car, of the door-locking mechanism having a sliding

spring-actuated bolt, a bell-crank lever connected to said bolt, and a pivoted detent connected to the other arm of said bell-crank lever and projecting at its free end into the path of said car, substantially as specified. 15

In testimony that I claim the foregoing as my own I have hereto affixed my signature in 20 the presence of two witnesses.

WILLIAM VEENSCHOTEN.
